UNITED STATES PATENT OFFICE

123,201

DESIGN FOR A PORTABLE LIGHT PLANT

Thomas Jackson, Detroit, Mich., assignor to Continental Motors Corporation, Detroit, Mich., a corporation of Virginia

Application June 30, 1938, Serial No. 78,173

Term of patent 14 years

To all whom it may concern:

Be it known that I, Thomas Jackson, a citizen of the United States, residing at Detroit, in the county of Wayne and State of Michigan, have invented a new, original, and ornamental Design for Portable Light Plants, of which the following is a specification, reference being had to the accompanying drawings, forming part thereof.

Fig. 1 is a perspective view of a portable light plant showing my new design.

Fig. 2 is a perspective view thereof as looking from the opposite side of the showing in Fig. 1, and

Fig. 3 is a top plan view of the light plant as illustrated in Figs. 1 and 2.

I claim:

The ornamental design for a portable light plant, as shown.

THOMAS JACKSON.
